UNITED STATES PATENT OFFICE.

LOUIS P. PROSSEN, OF NEW YORK, N. Y.

MACHINE FOR BENDING PISTON-RINGS AND THE LIKE.

1,373,095.

Specification of Letters Patent. Patented Mar. 29, 1921.

Application filed May 10, 1919. Serial No. 296,108.

To all whom it may concern:

Be it known that I, LOUIS P. PROSSEN, a citizen of the United States, residing at New York city, New York, have invented certain new and useful Improvements in Machines for Bending Piston-Rings and the like, of which the following is a clear, full, and exact description.

My invention relates to a machine for stressing and so bending metal, such as cold gray cast-iron. It is particularly adapted for so bending piston and packing rings.

My object is to improve and simplify machines for accomplishing the foregoing results.

In the preferred embodiment of my invention shown in the drawings,

Figure 1 is a three-quarter perspective view;

Fig. 2 is an enlarged front detail view showing the roller, ring and a portion of the track;

Fig. 3 is a central vertical section of Fig. 2;

Fig. 4 is a detail of a portion of the ring;

Fig. 5 is an enlarged detail showing the track, support and graduated adjusting means;

Figs. 6 and 7 are details; and

Fig. 8 is an enlarged view partially in section of the means for adjusting or flexing the track.

In the cold manufacture of cast iron packing rings, it is desirable in order to have the rings of a true circular form when in place, to stress the ring, and it is preferable that the stress given to the ring be varied along the same. In the case of a piston ring, for example, it is desirable to have the greatest pressure applied at the point opposite the point where the ring is separated, this pressure gradually decreasing in opposite directions toward the two ends of the ring. It is also desirable to be able to vary the pressure applied to adapt the operation to rings of varying thickness, size or material.

Referring to the drawings, 1 is a standard carrying an adjustable arm 2, provided with a support 3 for the pressure element. This pressure element for exerting pressure against the ring may be of various constructions, but I prefer a roller 4 which is provided with a series of teeth or projections around its circumference,

5 is an uncut piston ring. 6 is a support for the ring while being operated on, which, as shown, may be provided with a plurality of grooves substantially fitting the width of the piston rings to be operated on. Instead of making the track of circular form, I prefer to have it straight, but other forms may be used if desired. In the present embodiment I have shown it in the form of a bridge, the track proper being held at each end by supports 7 and 8 which are rounded at their lower edges. The track is adjustable in the supports by loosening the T-headed screw-bolts 9 to 12, these heads fitting in slots in the bed 13.

The track and roller are relatively movable, and I prefer to accomplish this by moving the track, which in this embodiment of my invention may be done by giving it a reciprocating motion such, for example, as by a power or other shaft 14, (connections not shown).

In order to vary the bending pressure at different portions of the work operated on, I prefer to make the track slightly flexible so that it may be flexed into the desired shape, in order to give the proper varying pressures wished for. In the present embodiment I have accomplished this by providing between the track and the bed an adjustable means 15, which, in the present example, I have made in the form of a threaded bolt 16 and nut, the latter carrying a rounded head 17 pressing against the underside of the track.

A suitable micrometer gage, such as 18, may be provided in order that the adjustment may be accurately graduated. By screwing up the nut 15, the center or other desired portion of the track may be flexed upward, as indicated in dotted lines in Fig. 5 (somewhat exaggerated), the track becoming a solid surface having the desired curvature, and when the bed is reciprocated, the pressure exerted upon the ring will gradually increase to the center of the track and then gradually diminish. By a construction of this character, the pressure applied to the ring may be varied as desired, and it is unnecessary to have a track of different shape for each thickness of piston rings operated on. Fig. 4 illustrates a portion of a ring operated on, the pressure, as shown by the indentations being less, for example, at the point 19 than at the point 20.

Obviously the rings may be rolled before

or after slotting them. It is desirable to grind the rings but this may be done before or after the rolling process.

By making the track flexible and adjustable, a wide range of tension and gap is possible. Of course more than one of the jacks or adjusting means 15 may be provided if desired. It will be obvious that my invention is not limited to operating upon a narrow ring, as wider rings, virtual cylinders or pot castings may be operated on in the same manner. By making the roller of suitable width, several rings may be rolled at the same time.

15. In order to adjust the roll or other pressure element toward and away from the work, I have mounted the roll on a shaft 21 carried by the arm 3, and which shaft has an extension 22 eccentric to the axis of the 20 shaft. The roller is pivoted on this extension. The arm 3 is split, as shown, and provided with a clamping screw 23 as shown in Fig. 2, which may be operated to cause the split portions of the arm to grasp the shaft 25 with considerable friction. The handle or arm 24 may be provided by which the eccentric shaft may be turned, thus raising the roll from the work or moving it down into engagement therewith.

30. In order to determine and, if desirable, vary the least pressure applied by the roll, I have provided a construction which will indicate the least pressure and which may be adjusted as desired. This may be in the 35 form of a spring scale 25 attached at one end to the handle 24 and at the other end to a cable 26 wound around the shaft of a ratchet and wheel 27. By suitably operating the ratchet wheel 27, any initial tension 40 desired may be exerted on the handle 24 and therefore by the roller on the ring. The operator also may press down on the handle 24 in order to release the roller from contact with the ring.

45. I am aware that my invention may be embodied in a variety of forms without departing from the primary purpose, and I therefore do not limit my claims to the particular embodiment or embodiments of my 50 invention herein illustrated or described.

What I claim as new is—

1. In a metal bending machine in combination, a pressure element and a relatively movable flexible track for the work, and adjustable means adapted to flex the track.

55. 2. In a metal bending machine in combination, a roughened pressure roll and a relatively movable flexible track for the work, and adjustable means adapted to flex the track.

3. In a metal bending machine in combination, a toothed roll and a relatively movable flexible track for the work, and adjustable means adapted to flex the track.

4. In a metal bending machine in combination, a pressure element and a relatively movable flexible track for the work in the form of a bridge, and adjustable means adapted to flex the track. 65

5. In a metal bending machine in combination, a pressure element and a flexible track for the work, and graduated adjustable means to flex the track. 70

6. In a metal bending machine in combination, a pressure element and a relatively movable flexible track for the work, adjustable means adapted to flex the track, and means for adjusting said pressure element toward and away from said track. 75

7. In a metal bending machine in combination, a pressure roll provided with teeth and a relatively flat track for the work in the form of a bridge, a bed or support for the bridge relatively movable back and forth with relation to the roll, said bridge being 85 provided with supports adjustable on said bed, and means for flexing the track comprising a graduated track flexing element, and means for moving the roll toward and from the track. 90

8. In a metal bending machine in combination, a track for the work, an eccentric, a pressure roll mounted on said eccentric, and means for moving said eccentric whereby said roll may be advanced and retracted 95 from the track.

9. In a metal bending machine in combination, a pressure element and a track for the work between which the work is adapted to be operated on, means for adjusting said pressure element toward and away from the work and means arranged to put a variable tension on said roller against the work. 100

10. In a metal bending machine in combination, a pressure element and a track for the work between which the work is adapted to be operated on, means for adjusting said pressure element toward and away from the work, and means arranged to put a variable tension on said roller against the work, said means comprising an adjustable and graduated spring scale. 105

Signed at New York city, N. Y., this 8 day of May 1919.

LOUIS P. PROSSEN.
